(57) **CLAIM**

The ornamental design for a measuring instrument case having flash cards, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a measuring instrument case having flash cards, in a closed state thereof, showing a first embodiment of our new design;

FIG. 2 is an alternative perspective view of FIG. 1;

FIG. 3 is top view of the measuring instrument case having flash cards of FIG. 1, in an open state thereof, showing the flash cards in a first position;

FIG. 4 is top view of the measuring instrument case having flash cards of FIG. 1, in an open state thereof, showing one of the flash cards in a second position;

FIG. 5 is a top view of the measuring instrument case having flash cards of FIG. 1, in an open state thereof, showing the flash cards in the second position;

FIG. 6 is a top view of FIG. 1;

FIG. 7 is a side view of FIG. 1, the opposite side view being a mirror image thereof;

FIG. 8 is a perspective view of a measuring instrument case having flash cards, in a closed state thereof, showing a second embodiment of our new design;

FIG. 9 is an alternative perspective view of FIG. 8;

FIG. 10 is top view of the measuring instrument case having flash cards of FIG. 8, in an open state thereof, showing the flash cards in a first position;

FIG. 11 is top view of the measuring instrument case having flash cards of FIG. 8, in an open state thereof, showing one of the flash cards in a second position;

FIG. 12 is a top view of the measuring instrument case having flash cards of FIG. 8, in an open state thereof, showing the flash cards in the second position;

FIG. 13 is a top view of FIG. 8; and,

FIG. 14 is a side view of FIG. 8, the opposite side view being a mirror image thereof.
